(57) **CLAIM**

The ornamental design for knob for a latch, as shown and
described.

DESCRIPTION

FIG. 1 is a perspective view of a knob for a latch showing
our new design;

FIG. 2 is a left side elevational view thereof;

FIG. 3 is a right side elevational view thereof;

FIG. 4 is a top plan view thereof;

FIG. 5 is a front view thereof;

FIG. 6 is a rear view thereof; and,

FIG. 7 is a bottom plan view thereof.

The broken lines in the figures are for illustrative purposes
only and form no part of the claimed design.
